UNITED STATES PATENT OFFICE.

HERBERT E. TAUTZ, OF MILWAUKEE, WISCONSIN, ASSIGNOR TO ELISHA JESSE CADY,
OF RIVER FOREST, ILLINOIS.

MICROMETER CALIPER.

Application filed March 7, 1924. Serial No. 697,448.

To all whom it may concern:

Be it known that I, HERBERT E. TAUTZ, a citizen of Germany, residing at Milwaukee, in the county of Milwaukee and State of Wisconsin, having invented certain new and useful Improvements in Micrometer Calipers, do hereby declare that the following is a full, clear, and exact description of the same, reference being had to the accompanying drawings:

The invention relates to micrometer calipers for measuring the thickness of various materials, and especially for measuring the thicknesses or points of different grades of paperstock in variations of one-thousandth part of an inch.

The invention consists in the matters hereinafter described and then pointed out in the appended claims, and its features are illustrated in the accompanying drawing, in which,

Fig. 1 is a vertical sectional view of the device partly in elevation showing the general arrangement of its parts;

Fig. 2 is a sectional view on the line 2—2 in Fig. 1 showing the casing with associated elements, parts being broken away;

Fig. 3 is a detail horizontal sectional view on an enlarged scale looking in the direction of the arrows on the line 3—3 in Fig. 1;

Fig. 4 is a similar sectional view on the same line looking in the opposite direction, and;

Fig. 5 is a detail sectional view on an enlarged scale:

As shown in the drawings the frame comprises the usual base 1 having a central anvil 2, an integral upwardly curved bracket-arm 3 and an integral upper circular block 4, provided with an open-top circular chamber 5 and with a lower circular bore or well 6 open at its lower end and concentric with the anvil. A plunger sleeve 7 is seated in the well 6 in line with the anvil 2 and capable of vertical movement in its seat; the lower end of the sleeve carries a headed bolt 8 whose outer end engages a correspondingly threaded hole in a measuring foot 9, which seats on the anvil when the pointer 50 of the machine is at zero. The upper end of the sleeve 7 extends into the chamber 5 where it is provided with a head 10 having a circumferential groove which receives the opposite inwardly directed lugs 11 of a

yoke 12 of an operating lever or handle 13 which extends out through a slot 14 in the block 4 and is pivoted at 15 thereon. The operating handle 13 is stressed by a coil-spring 16 seated in a cavity 17 in the arm 3 to normally seat the foot 9 on the anvil 60 2; in practice I prefer to employ a ball 18 seated in the upper portion of the cavity between the spring 16 and handle 13.

The top of the chamber 5 supports a circular dial casing whose bottom plate 19 is attached to the block 4 by screws 20 and carries a dial-plate 21 provided with a circular measuring scale on which the indicating graduations or divisions are marked in units from zero to 200 and over which a revolute pointer 22 travels. The perimeter of the plate 19 has an upturned flange 23 to support a glass closure plate 24 spaced above the pointer, and held in position by a flanged retaining ring 25. The plate 19 is provided with a central opening co-axial with the sleeve 7, and a circular bushing 26 projects down through this opening into the sleeve, being suspended therein by its flanged head 27 which is carried by the plate 19. The bushing 26 is held against upward displacement or movement by a split-collar 28 which is located in the chamber 5 and is clamped tightly on the upper portion of the bushing below the plate 19 by a transverse-headed screw 29. The collar 28 has a radial handle 30 extending laterally through a radial notch 31 in the block 4 to allow the handle to swing through a suitable arc for a purpose hereinafter described. The bushing 26 and its collar 28 are normally held against rotation or axial turning by a circular friction washer 32 interposed between the collar and the bottom plate 19 of the casing. The bushing 26 extends down into sleeve 7 a suitable distance, its lower portion preferably being longitudinally slotted, as shown at 33 from a point slightly below the collar 28 to approximately its lower end where it carries an integral circular nut 34 which fits loosely within the sleeve 7 and has a central threaded opening to engage a correspondingly threaded vertical screw-shaft 35 having five (5) threads to the inch, so that the shaft moves vertically one-fifth ($\frac{1}{5}$) of an inch 100 at each revolution in the nut or two-hundred thousandths represented in points of one-thousandths of an inch. The screw-

shaft 35 is moved upwardly by the sleeve 7, a ball 36 seated in the reduced lower end of the sleeve below the lower end of the shaft preferably being interposed between these parts, and the upper portion of the screw-shaft above its threaded portion is reduced and angular in cross-section and enters a correspondingly shaped opening in the lower end of a pointer-thimble 37 which fits revolvably within the upper end of the bushing 26. The thimble 37 has a flange 38 supported on the head 27 of the bushing 26, and carries the pointer 22 which is clamped on this flange by a cap 39 held in place by a headed-bolt 40 threaded into the thimble. The thimble is free to revolve in the bushing 26 to turn the pointer but is held against upward movement or displacement by a pin 41 fixed in the bushing and entering an annular groove 42 in the thimble. By this organization the angular end of the screw-shaft 35 freely moves vertically in the pointer-thimble 37 but turns the latter to move the pointer away from zero when the shaft is revolved by longitudinally moving through its nut 34 under the upward pressure of the sleeve 7 when the latter is raised by the handle 13. The pointer is spring stressed to normally stand at zero on the scale by a long coil-spring 43 located in the bushing 26 around the screw-shaft 35 and anchored at its opposite ends to the nut 34 and the thimble 37 respectively to react between the bushing and screw-shaft; the lower end of the thimble within the bushing is reduced in cross-sectional area to form a shoulder 44 for seating the spring, and the slotted or skeleton construction of the bushing at 33 affords access to its interior to assemble the spring in place. The pressure or stress of the spring 43 being directly and positively applied on the pointer-thimble takes up all wear and lost motion between the upper angular end of the screw-shaft 35 and the thimble and between the lower threaded end of this shaft and its nut 34, and also holds the shaft down on the ball 36.

In using the machine, the parts normally stand in the position shown in Figs. 1 and 2, with the measuring foot on the anvil, the pointer at zero, and the operating handle swung up. Upon rocking the handle down the spring 16 is put under tension, the sleeve 7 and the screw-shaft 35 are moved up, and the latter is rotated in its passage through the nut 34 to rotate the pointer-thimble; whereby the spring 43 is wound up, the foot 9 is raised and the pointer 22 moved on the scale away from zero. If the handle 13 is moved to its limit the shaft 35 and pointer 22 will be given slightly more than a full revolution and the pointer will be moved over the scale slightly beyond 200, and if the stock to be calipered is now inserted on the

anvil under the foot and the handle released the springs 16 and 43 will return the parts toward their normal positions until the foot reaches the stock on the anvil, when their further movement will be arrested and the pointer will stop at the appropriate indicating mark on the dial. When the stock to be calipered is thin or light the movement of the pointer need not exceed the point to raise the foot far enough to allow the stock to be inserted on the anvil, the screw-shaft need not necessarily be given a full revolution, but in any event the descent of the foot is arrested by the stock with the pointer at the appropriate unit to give direct indication and reading of the thickness of the stock.

In the use of the machine the collar 28 engages the bushing 26 tight enough to hold the latter from turning by the thrust of the screw-shaft on the nut 34 under normal operations, and to overcome the resistance of the friction washer 32 to turn the bushing in either direction by the handle 30 when it is desired to co-ordinate the foot 9 on the anvil 2 and the pointer 22 at zero on the scale. This latter capability is of advantage in both the assembling and subsequent use of the device; in setting up or calibrating the instrument the bushing may be turned by the collar and its handle to overcome the friction of the washer and revolve the screw-shaft and pointer-thimble one way or the other until the adjustment is exact to bring the pointer at zero on the scale when the foot 9 is on the anvil 2.

The construction and arrangement of parts may be varied without departing from my invention. For example, the relatively stationary member exemplified by the nut 34 for rotating the screw-shaft may be of any suitable form when the handle lifts the latter, the main consideration in this respect being that this member shall rotate the shaft, whereby all gears between the shaft and the operating handle are eliminated. Also, the angle of the helix of the screw is variable so long as slight vertical pressure on it will revolve it in the sleeve so that friction is reduced.

I claim:

1. In a caliper device, an anvil, a reciprocating measuring-foot in line with the anvil, a handle to move the foot, a scale and a revoluble pointer, a screw-shaft actuating the pointer, means between the shaft and foot to operate the former longitudinally when the latter is moved, and means engaging the screw-shaft to rotate it when it is moved by said operating-means.

2. In a caliper device, an anvil, a reciprocating measuring-foot in the line of the anvil, a handle to move the foot, a scale and a revoluble pointer, a screw-shaft actuating the pointer, a stationary nut engaging the

shaft, and means between the shaft and foot to operate the shaft through the nut when the foot is moved.

3. In a caliper device, an anvil, a reciprocating measuring-foot in line with the anvil and having a handle, a reciprocating screw-shaft, means between the foot and shaft to transmit the motion of the former to the latter, a scale and a revolute pointer, actuating connections between the shaft and pointer, and a stationary member engaging the screw-shaft whereby the shaft is rotated when it is reciprocated.

4. In a caliper device, an anvil, a reciprocating measuring-foot in line with the anvil and having a handle, a reciprocating screw-shaft having an angular upper end, means between the foot and shaft to transmit the motion of the former to the latter, a scale and revolute pointer, a thimble actuating the pointer and having an angular opening to slidably engage the angular end of the shaft, and a stationary member engaging the screw-shaft whereby the shaft is rotated when it is reciprocated.

5. In a caliper device, a frame having an anvil and an elongated well in line with said anvil, a reciprocating screw-shaft in the well, a pointer actuated by the shaft, a dial for the pointer, a reciprocating sleeve mounted in the well and carrying a measuring foot, a spring yieldingly maintaining the pointer at zero on the dial, means between the shaft and sleeve to move the shaft when the sleeve is moved, and means to rotate the shaft when it is moved by the sleeve.

6. In a caliper device, a frame having an anvil and an elongated well in line with said anvil, a screw-shaft in the well, a thimble actuated by the shaft and carrying a pointer, a dial for the pointer, a reciprocating sleeve mounted in the well and carrying a measuring foot, a stationary member engaging the screw-shaft, a spring between said member and thimble, and means between the shaft and sleeve to move the shaft when the sleeve is moved.

7. In a caliper device, an anvil, a reciprocating sleeve carrying a measuring foot in line with the anvil and having a handle, a stationary bushing projecting into the sleeve, a reciprocating screw-shaft in the bushing, a coil-spring reacting between the

bushing and shaft, means between the sleeve and shaft to transmit the motion of the former to the latter, means engaging the screw-shaft to rotate it when it is reciprocated, a pointer actuated by the shaft, and a scale for said pointer.

8. In a caliper device, an anvil, a reciprocating sleeve carrying a measuring foot in line with the anvil and having a handle, a stationary bushing projecting into the sleeve and having a nut at its lower end, a thimble rotatably mounted in the upper end of the bushing and carrying a pointer, a reciprocating screw-shaft in the bushing threaded through said nut and slidably engaging and turning said thimble, a coil-spring surrounding said shaft in the bushing and connected at its ends to the nut and thimble, and means between the sleeve and shaft to transmit the motion of the former to the latter.

9. In a caliper device, a frame having an anvil and a chamber in line with said anvil, a bushing in the chamber, a screw-shaft in the bushing and having threaded connection therewith, a pointer actuated by the shaft, a dial for the pointer, a sleeve slidably mounted in the frame and carrying a measuring foot, actuating means between the sleeve and shaft, and means constructed to hold the bushing against turning when the shaft is rotated and to turn the bushing on the shaft to adjust the pointer to its zero position on the dial.

10. In a caliper device, a frame having an anvil and a chamber in line with said anvil, a bushing in the chamber, a screw-shaft in the bushing and having threaded engagement therewith, a pointer actuated by the shaft, a dial for the pointer, a sleeve slidably mounted in the frame and carrying a measuring foot, actuating means between the sleeve and shaft, a split-collar in the chamber normally held against turning when the shaft is rotated and frictionally engaging the bushing to turn the latter on the shaft to adjust the pointer to its zero position on the dial, and a handle to turn the bushing.

In testimony whereof I hereto affix my signature.

H. E. TAUTZ.
